GARMENT HANGER

Rouel R. Campbell, Los Angeles, Calif.

Application August 14, 1958, Serial No. 755,098

6 Claims. (Cl. 223—96)

This invention relates to a garment hanger of the general type employed for suspending a garment from an overhead rod in a clothes closet. More particularly, the invention pertains to a hanger that grips a garment for suspension in a flat state.

For widespread usage, a garment hanger of this type should be of simple inexpensive construction and should be not only efficient for its purpose but also durable for a long service life. Simplicity requires a construction having a few parts and durability requires minimum wear and fatigue of the moving parts.

If a hanger is constructed to grip a garment, it must have at least one clamp means and a hook for supporting the clamp means from an overhead rod. The clamp means must grip a garment at widely spaced points for the garment to hang properly, and it is more economical to employ two spaced clamp means for this purpose than a single clamp means of relatively great width. The minimum structure, then, may comprise two clamp means, a transverse support means such as a transverse bar or the like for mounting the two clamp means in spaced relation, and a hook to support the transverse bar.

A primary feature of the invention is that each of these pairs of jaws comprises a single piece of formed resilient sheet metal. This single piece of sheet metal is equivalent to a jaw assembly comprising several parts since it not only provides a pair of jaws but also provides for biasing the jaws to open position and, in addition, provides releasable latch means to hold the jaws closed on a garment.

Another important feature is that the single piece construction insures dependable engagement of the jaws with a garment by using the weight of the garment itself to keep the jaws closed.

Still another feature is that each pair of jaws may be closed and latched simply by shifting the pair of jaws bodily downward relative to the lateral support means, no manipulation of a latch mechanism being necessary.

A further feature that is both unique and important is that while the jaws stay closed in response to the weight of the garment, nevertheless, the jaws may be quickly and easily released by merely swinging the two pairs of jaws laterally. Thus, to release the garment from the hanger it is sufficient merely to tug the flat garment edgewise.

In the preferred practice of the invention disclosed herein, these various features are provided by bending a band of spring metal to the general configuration of a clothes pin to form the required pair of jaws and by further slitting and offsetting the metal of each jaw to form at least one metal loop extending toward the other jaw. These loop elements from the two jaws overlap to form an opening by means of which the pair of jaws are mounted on the transverse bar, the bar being carried by the usual overhead hook. To stabilize the pair of jaws on the transverse bar, one jaw is provided with a single offset

2

loop element and the other has a pair of offset loop elements which straddle the single loop element.

The spring metal band is biased to yieldingly urge the two jaws apart. Consequently, the opening formed by the overlapping loop elements tends to contract with resulting pressure gripping of the transverse bar when the two jaws are open. If the jaws are closed, the opening is expanded but the expanded configuration provides a relatively narrow upper recess in which the transverse bar seats to latch the two jaws in closed positions.

The various features and advantages of the invention will be apparent from the detailed description considered with the accompanying drawings.

In the drawings, which are to be regarded as merely illustrative:

Fig. 1 is a side elevation of the presently preferred embodiment of the garment hanger;

Fig. 1a is a transverse section taken as indicated by the line 1a—1a of Fig. 1 to show how the garment hanger may be provided with a hook to support a second similar hanger. In this manner a number of the hangers may be hung in a vertical series;

Fig. 2 is a transverse section taken as indicated by the line 2—2 of Fig. 1 showing a pair of jaws in open state and showing how the spreading apart of the jaws contracts the central opening through which the transverse bar extends;

Fig. 3 is a view similar to Fig. 2 showing the jaws closed on a garment and showing how the jaws are latched in closed position by the seating of the transverse bar in an upper recess of the opening that is formed by the overlapping loop elements;

Fig. 4 is a side elevation of a pair of jaws in the closed state shown in Fig. 3;

Fig. 5 is a plan view of a sheet metal blank at an intermediate stage in the processing of the blank to form a pair of jaws;

Fig. 6 is a side elevation of the blank after the blank has been completely processed but before the blank is mounted on the transverse bar;

Fig. 7 is a plan view of a second form of blank that may be employed in an alternate practice of the invention; and

Fig. 8 is an end elevation of a clamp means formed by the second blank, the clamp means being shown with its jaws gripping a garment.

As shown in Fig. 1, the principal parts of the first embodiment of the invention comprise a transverse support bar 10, an upwardly extending hook member 12 for engagement with an overhead rod in a clothes closet, and two clamp means, each generally designated by numeral 14, slidably mounted on the transverse bar. The hook member 12 is a wire member spot welded or otherwise bonded to the transverse bar 10 and preferably the wire that forms the hook member 12 also forms a lower hook-shaped loop 15 to enable one garment hanger to be supported by another garment hanger. Thus, the hook member 12 of a second garment hanger may be supported by the hook-shaped loop 15 to carry a second garment. In the construction shown, the hook member 12 is provided with a smooth plastic knob 16 on its end, and the transverse bar 10 is provided with similar plastic knobs 18 on its opposite ends. These knobs may be omitted if desired.

The construction of each of the clamp means 14 may be understood by referring first to Fig. 5 which shows a blank 20 that is used to form a clamp means. The blank 20 is of spring metal and may comprise a length of band stock. Since the two ends of the blank 20 form the ends of the two pairs of jaws, the two ends may be offset to form dimples 22. The bare dimples may be used for

frictionally engaging a garment but preferably the two jaws of a clamp means 14 are provided with rubber-like bodies for this purpose, as indicated at 24 in Figs. 1-4, and the dimples 22 provide effective anchorage for the rubber-like bodies.

The blank 20 in Fig. 5 has a pair of parallel longitudinal slits 25 on one of its longitudinal halves which form a corresponding central strip of metal 26 and is provided on its other longitudinal path with a similar pair of parallel longitudinal slits 28 which are spaced further apart to form a corresponding pair of marginal strips of metal 30.

The completion of the clamping means consists simply in forming the slotted blank 20 to the configuration shown in Fig. 6 to provide two jaws or clamp arms 32 and 34 interconnected by an upper central loop 35. The strip of metal 26 of the blank 20 is offset to form a single loop element 26a on the jaw 32 extending toward the second jaw 34. In like manner, the two marginal metal strips 30 of the blank 20 formed by the two slits 28 are bent to form a pair of loop elements 30a on the jaw 34 that extends toward the jaw 32 in positions aligned to straddle the single loop element 26a. In the present practice of the invention the transverse support bar 10 has a flat face 40 on one of its sides and the pair of loop elements 30a are formed with a straight or flat portion 42 to cooperate with the flat face of the transverse support rod to maintain the clamp means in vertical position when the jaws are open.

With the metal blank 20 formed to the configuration shown in Fig. 6, it is apparent that the two jaws 32 and 34 may be forced toward each other to cause the loop elements 26a and 30a to overlap and thereby form a contracted opening 44 through which the transverse bar 10 may extend as shown in Fig. 2. Since the clamp means tends to return to the configuration shown in Fig. 6, it is apparent that the clamp means yieldingly grips the transverse bar 10, and since the flat portions 42 of the two loop elements 30a lie snug against the flat side face 40 of the transverse bar, it is apparent that when the clamp means is open it tends to keep a vertical position on the transverse bar. It is also apparent that since the two loop elements 30a straddle the loop element 26a, the clamp means 14 grips the transverse support rod 10 in a stable manner with no tendency for the clamp means to twist about its vertical axis.

To cause the two jaws 32 and 34 to close, the overlap of the loop elements 26a and 30a must be increased with consequent expansion of the opening 44 to the expanded configuration shown in Fig. 3. The overlapping loop elements 26a and 30a are so shaped as to form the expanded opening 44 with an upper restricted recess 45, as shown in Fig. 3, so that closing of the jaws 32 and 34 on a garment 36 merely requires relative movement between the clamp means and the transverse bar 10 to cause the transverse bar to enter the restricted recess 45. The recess is restricted in the sense that when the transverse bar 10 is in the recess, the recess has a somewhat narrow entrance whereby the transverse support rod 10 tends to remain in the recess. It is to be noted, however, that the recess need not necessarily have a restricted entrance since the weight of the garment 36 in pulling down on the clamp means tends to maintain the relationship shown in Fig. 3.

In this particular practice of the invention, the clamp means also cooperates with the flat side face of the support rod 10 to tend to maintain the clamp means vertical when the jaws are closed but it is to be noted that the weight of the garment 36 also tends to keep the clamp means vertical. The two loop elements 30a have straight or flat portions 46 as shown in Figs. 2 and 6 which rest snug against the flat face 40 of the transverse bar 10 when the jaws are closed as may be seen in Fig. 3.

One convenient procedure for closing a clamp means 14 into gripping engagement with a garment 36 is by

finger manipulation in the manner indicated in phantom in Figs. 1 and 2. In this procedure, the operator's thumb 48 presses downward against the top loop 35 of the clamp means, and simultaneously the first and second fingers 50 and 52 of the operator press upward against the underside of the transverse bar 10. An alternate procedure which is also convenient, is to press the two jaws 34 and 32 together by one hand to grip a garment 36 and then simply pull downward on the clamp means while holding the transverse bar 10 in the other hand.

A garment 36 may be released by shifting the transverse bar 10 downward out of the recess 45. An important feature of the invention is that the release action may be carried out by rocking a closed clamp means laterally in the plane of the transverse rod thereby to cause the transverse bar to snap out of the recess 45 of the clamp means. In fact, it is merely necessary to tug the garment edgewise to cause both of the clamp means to snap open.

Figs. 7 and 8 show how an alternate form of clamp means, generally designed 55 may be shaped from a metal blank 56. The metal blank 56 in Fig. 7 is formed with a central longitudinal slot 58 at one end of one-third the width of the blank to form a pair of parallel jaw members 60. The other end of the blank is reduced in width to provide a cooperating single jaw member 62 of the same length and width as the slot 58. Thus, a plurality of blanks 56 may be stamped out of band stock without waste.

The blank 56 shown in Fig. 7 is then serrated or roughened at the end of each of the jaw members 60 and 62 as indicated at 64 in Fig. 7 to provide adequate anchorage for rubber-like bodies 65 that are of the same character as the previously mentioned rubber-like bodies 24 and 25 serve the same purpose. It will be noted in Fig. 8 that the two jaws 60 and the single jaw 62 are offset to form overlapping loop elements, with the loop elements 60a of the two jaw members 60 straddling the single loop element 62a of the jaw member 62 and forming therewith an opening 66 to receive the previously mentioned transverse support bar 10. The loop element 62a has a flat portion 72 which serves the same purpose as the flat portions 42 in the first embodiment. Fig. 8 shows the opening 66 in its expanded state with the transverse support bar 10 in an upper restricted recess 68 formed by the opening. Fig. 8 also shows that the metal blank 56 may be bent to form a circular top loop 70 interconnecting the jaws 60 and 62.

This second form of the invention functions in the same manner as the first form.

My description in specific detail of the presently preferred practice of the invention will suggest various changes, substitutions and other departures from my disclosure within the spirit and scope of the appended claims.

55 I claim:

1. In a garment hanger, the combination of: a transverse support member; a hook member extending upward from said transverse member for support thereof; and at least one clamp means mounted on said transverse member, said clamp means comprising a pair of jaws, each of said jaws having a loop element extending toward the other jaw, the oppositely extending loop elements overlapping to form an opening through which said transverse member extends, said opening having an expanded configuration when the jaws are closed together to grip a garment and a contracted configuration when the jaws are spread apart, said jaws being resiliently biased to spread apart with consequent contraction of said opening, said opening at its expanded configuration being formed with a recess at its upper end to straddle said transverse member and grip the transverse member from opposite sides whereby the clamp means may be moved relative to the transverse member to shift the transverse member 65 into said recess to cause the jaws to grip a garment and
- 60
- 65
- 70
- 75

to shift the transverse member out of the recess to cause the jaws to open to release a garment.

2. A garment hanger as set forth in claim 1 in which said jaws are resilient sheet members slitted and offset to form said loop elements.

3. A garment hanger as set forth in claim 2 in which said clamp means comprises a one piece resilient sheet member.

4. A garment hanger as set forth in claim 1 in which one of said jaws has a single loop element and the other jaw has a pair of loop elements straddling the single loop element.

5. A garment hanger as set forth in claim 1 in which

10 5

said opening has a straight side portion at its contracted configuration and said transverse member has a corresponding flat portion for pressure engagement therewith to yieldingly hold said clamp means in a substantially vertical position.

6. A garment hanger as set forth in claim 1 in which said loop elements are off-set portions.
